(57) **CLAIM**

The ornamental design for a control unit for air compressor, as shown and described.

DESCRIPTION

FIG. 1 is a front, top and left side perspective view of a control unit for air compressor showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded front, top, and left side perspective view thereof. The broken line portions of FIGS. 3 and 8 are included to show unclaimed subject matter that forms no part of the claimed design.

1 Claim, 6 Drawing Sheets
